Fig. 4

To all whom it may concern:

Be it known that I, Thomas E. Kallmeyer, a citizen of the United States of America and a resident of Colerain Township, in the county of Hamilton and the State of Ohio, have invented a new, original, and ornamental Design for a Mail Case, of which the following is a specification, reference being made to the accompanying drawing, forming a part thereof.

Fig. 1 is a perspective view of a mail case showing my new design;

Fig. 2 is a top plan view;

Fig. 3 is a side elevational view; and

Fig. 4 is a bottom plan view thereof.

I claim:

The ornamental design for a mail case, as shown.
